PROCESS OF SWEETENING A SOUR
HYDROCARBON DISTILLATE

David Louis Yabroff and John Wilkinson Givens,
Berkeley, Calif., assignors to Shell Develop-
ment Company, San Francisco, Calif., a cor-
poration of Delaware

Application May 18, 1936, Serial No. 80,374

11 Claims. (Cl. 196—32)

This invention relates to the removal of weakly acid reacting organic substances from solutions in organic liquids of the type of hydrocarbons, and in particular deals with the removal of mercaptans from petroleum distillates.

It is frequently necessary to eliminate small quantities of organic acidic components such as mercaptans, phenols, naphthenic acids, fatty acids, etc., from their solutions in substantially neutral hydrocarbon type liquids. The term, substantially neutral hydrocarbon type liquids, as herein used, refers to hydrophobe normally liquid organic substances which are neutral or slightly basic, such as the liquid hydrocarbons derived from petroleum, benzene, toluene, xylene, substituted normally liquid hydrocarbons which are substantially insoluble in water, for instance, chlorinated hydrocarbons, of which chlor ethane, ethylene dichloride, tri-chlorethylene, carbon tetra chloride, chlor propane, chlorbutylene, chlorbenzene, brom benzene, are examples; or nitro hydrocarbons, for example, nitroethane, nitrobenzene; or other nitrogen containing hydrocarbons such as the amylamines, aniline, pyridine, petroleum bases, etc.

Heretofore it has been the practice to treat solutions containing organic acidic impurities with aqueous or alcoholic alkali hydroxides of various strengths. In many instances, however, alkali hydroxides fail to eliminate the acidic substances to the desired degree. The reason commonly assigned to this shortcoming was that the acidities of some of the acids are too low to enable their combining with the alkali hydroxides.

An improvement was brought about by employing countercurrent extraction and by using large excesses of hydroxide solutions over the amounts of liquid to be extracted. However, this treatment is cumbersome and expensive because it requires the handling of excessively large quantities of chemicals, and in some instances such as in the sweetening of sour West Texas gasoline, which involves extractions of mercaptans having 5 or more carbon atoms, it was found practically impossible to effect sweetening by caustic treatment only, even with a large excess of aqueous caustic.

We have discovered that the true reason for the difficulty of extracting certain of the organic acids from their solutions is not one of excessively low acidity, but of insolubility in the extraction solvent, this insolubility being responsible for an unfavorable distribution of the acid between the extraction solvent and the original solution. We have overcome this unfavorable distribution by

extracting the organic weakly acidic compounds from their solutions in hydrocarbon type solvents by treatment with a quaternary ammonium base, under conditions to form two phases, and separating these phases.

Quaternary ammonium bases may be used as such, or in suitable solution and, if desired, in combination with alkali hydroxides or other strong bases, such as ammonia, calcium hydroxide, etc. The extraction may be carried out at any temperature below the boiling points of the liquids under the conditions of the treatment. We prefer, however, to extract at temperatures not substantially higher than normal room temperatures, extraction efficiencies declining with increasing temperatures. Since practically all quaternary ammonium bases are solids at room temperature, we normally prefer to use them in solution of a suitable solvent, particularly water, although other non-acid solvents such as anhydrous liquid ammonia or aqueous organic solvents which are miscible with water in all proportions and substantially non-miscible with hydrocarbon type liquids, may also be used, of which organic liquids the following are examples: lower alcohols, comprising the mono- and poly-hydric alcohols which are liquid at normal room temperatures, specifically, methyl, ethyl, propyl alcohols, glycol, glycerine; chlorhydrin; amino alcohols, alcohol ethers, such as ethylene, glycol mono-ethyl ether, lower ketones such as acetone, methyl ethyl ketone; lower di-amines, such as ethylene di-amine, etc.

Some of the hydrocarbon type liquids and organic solvents for the base as herein mentioned, may be miscible with each other. Since, however, the miscibility properties of these liquids are generally well known, it shall be within the skill of the operator to choose from the given list those solvents which are substantially non-miscible with a particular type hydrocarbon liquid to be extracted.

The peculiar suitability of quaternary ammonium bases for the purpose of extracting organic acids, as herein described, appears to be due to a combination of three properties, namely, solubility in water, high alkalinity and selective solvent power for organic compounds containing polar substitution groups. The relative influence of these properties is discussed below.

Solubility in water is important, because water besides being a cheap solvent, renders the quaternary ammonium base fully immiscible with hydrocarbon type liquids, thereby preventing losses of the former.

The extraction of an acidic solute RH from the solution in a hydrocarbon type liquid by means of an aqueous base solution, can be formulated by the following equilibria:

This formula, in which R is an organic acid radical and B is a base radical indicates that there are at least two main equilibria, marked (1) and (2) respectively, which control the extraction efficiency. Equilibrium (1) represents the distribution of unneutralized free acid between the hydrocarbon and aqueous phases. It depends upon the relative solubilities of the free acid in the two phases. Since the solubility of the acid in the hydrocarbon phase is fixed, or at least not controllable, the distribution then becomes the sole function of the solvent power of the aqueous solution.

Equilibrium (2) relating to the ratios of unneutralized free acid and salt of the acid in the aqueous phase, depends upon the relative activities of the hydroxide ions and water. Since high hydroxide ion concentration is favorable to the formation of the salt RB, which is assumed to be insoluble in the hydrocarbon liquid, high alkalinity of the base is therefore important. Assuming that equilibrium (2) is constant, it will be seen that the final equilibrium between solute RH in the hydrocarbon phase, and solutes RH and RB in the aqueous phase, is then solely dependent on the solubility of the free acid in the aqueous phase. In other words, for a given degree of hydrolysis of the salt RB in the aqueous phase, the partition coefficient which is concentration of solute in the aqueous phase per concentration of the solute in the hydrocarbon phase depends only on the solvent power of the aqueous phase for the unneutralized free acid.

Quaternary ammonium bases suitable for the described purpose, have the formula

in which R₁ to R₄ are alkyl, unsaturated alkyl, 50 aryl, or aralkyl radicals, which may contain polar substitution groups selected from the class of —OH, —NH₂, —NO₂ and halogen, or heterocyclic radicals which are linked to the quaternary nitrogen atom by way of a carbon atom, which carbon atom may or may not be part of the heterocyclic ring. The lower ones of these bases are soluble in water, solubility tending to decrease with increasing size of the organic radical.

We have found that the nature of the radical 60 has a considerable influence on the solvent power of the quaternary ammonium bases for organic compounds, such as the organic acids of the type herein described. In the order of increasing solvent power, the radicals are normal aliphatic, 65 branched aliphatic with secondary carbon atom, branched aliphatic with tertiary carbon atom, olefinic, and aromatic. An increase in the number of carbon atoms within a group normally raises the solvent power of the base. Polar 70 groups tend to lower the solvent power, but raise the solubility of the base in water. Thus, in general, we prefer quaternary ammonium bases containing radicals without polar substitution groups, at least one of which radicals is aromatic. 75 For instance, we prefer trimethyl tolyl ammo-

nium hydroxide to either tetramethyl or trimethyl cresyl ammonium hydroxide, although even the latter give excellent results.

The concentration of quaternary ammonium base in an aqueous solvent required to effect substantially complete extraction of an organic acid solute from an organic liquid depends on the nature of the solute. Obviously the solvent effect increases with increasing concentration. In some instances a 10% aqueous solution may 10 prove sufficient, but normally we prefer to employ solutions of concentrations of the order of 30 to 50%. Since, however, there is no general rule by which to define an optimum concentration, economical factors having to be considered, 15 we do not wish to be limited by any specific concentration range.

As previously pointed out, high alkalinity of the base solution is desirable. To increase the alkalinity, we often add to the base solution an 20 alkali hydroxide, which addition greatly enhances the extraction efficiency.

In order to explain the importance of our invention more fully, we resort to the theory of countercurrent extraction of two mutually immiscible liquids, namely, a feed containing the solute to be extracted and the extraction solvent which flow in countercurrent to each other through a multi-stage extraction apparatus. The mathematical treatment of this problem 30 leads to the formula:

$$\% \text{ solute left in feed} =$$

$$\frac{1-SK}{1-(SK)^n} + 1$$

in which S=solvent to feed ratio

K=partition coefficient=

$$\frac{\text{concentration of solute in extraction phase}}{\text{concentration of solute in raffinate phase}}$$

40

n=number of stages

In the attached drawing, to which it is now referred, a graph is shown in which the product SK of solvent to feed ratio S and partition coefficient K is plotted against percent solute removed from the feed for the various numbers of extraction stages n, in accordance with the above formula. From this drawing it will be seen that the percent removed increases rapidly with increasing SK. Thus, SK should be as high as possible, at least higher than 1, because otherwise all of the solute cannot be removed from the feed even with infinite number of stages. Since, however, S should be as low as possible to minimize size of treating equipment, pumping cost and loss of solvent, it is necessary that K be high. Moreover, the number of extraction stages should be reduced to a minimum to reduce the cost of equipment, which demands a further increase in the value of K.

Applying the graph to the extraction of mercaptans and knowing that the maximum amount of mercaptan sulfur tolerable in a sweet hydrocarbon distillate is .0004%, it is possible to determine the solvent to feed ratio and number of stages which are necessary to produce a "doctor" sweet distillate, if the average K value of the solvent against the hydrocarbon distillate for the mercaptans therein contained is known.

The following examples, in which the advantage of extracting mercaptans with a quaternary ammonium base over extraction with alkali hydroxide is shown, serve to illustrate this point:

It is desired to sweeten a West Texas straight

run gasoline containing .0782% mercaptan sulfur. To effect sweetening and to reduce the mercaptan sulfur content to .0004%, 99.45% of the mercaptan sulfur must be removed. According to the graph, a 4-stage extraction at an SK value of 4, or a 3-stage extraction at an SK value of 8, gives the desired result.

The average K value for the mercaptans in this particular gasoline against a 2.5 normal aqueous sodium hydroxide solution, was found to be about .25. Thus, to sweeten this gasoline in 4 stages about 16 volumes of aqueous sodium hydroxide, and in a 3-stage extraction 32 volumes, per volume of gasoline are required. Obviously, such a ratio of caustic to gasoline is uneconomical.

The K value of a 2.5 normal aqueous quaternary ammonium base, such as tri-methyl benzyl ammonium hydroxide, for the mercaptans in the above West Texas gasoline is about 9. Again according to the graph, sweetening can be achieved in a 4-stage extraction with .45 volumes of quaternary ammonium base, and in a 3-stage extraction with .90 volumes per volume of gasoline. Thus the volume of quaternary ammonium base which accomplishes sweetening is about 1/35 of the volume of sodium hydroxide of equal normality required to effect the same result.

If now to the 2.5 normal sodium hydroxide solution various amounts of tri-methyl benzyl ammonium hydroxide are added, the K values for the mercaptans in the above West Texas gasoline are as follows:

35	% tri-methyl benzyl ammonium hydroxide in 2.5 normal aqueous sodium hydroxide	Average K 20°C.
10		.9
20		3.3
40		51.2

40 With a K value of 50 the amounts of solvent necessary to sweeten the gasoline are .08 volumes in a 4-stage extraction and .16 volumes in a 3-stage extraction per volume of gasoline, which 45 volumes are about 1/200 of those required to sweeten with 2.5 normal aqueous alkali hydroxide in the absence of quaternary ammonium base, and about 1/5 of those required of the 2.5 normal quaternary ammonium base in the absence of 50 alkali hydroxide.

Recovery of the quaternary ammonium base can be had by several methods, which methods depend largely on the type of acids extracted. If mercaptans are the only acids contained in the 55 extract, steaming at elevated temperature will remove the largest part. Preferable, however, is an oxidation treatment such as electrolytic oxidation; or blowing with air or oxygen, if desired, in the presence of catalysts comprising heavy 60 metals having at least two oxidation stages, their oxides and salts, particularly copper. During this treatment mercaptans are converted to disulfides, which disulfides can be removed by washing the base solvent with naphtha and the 65 like or by skimming and/or steaming.

If acids other than mercaptans such as hydrogen sulfide, aromatic hydroxy compounds, naphthenic acids, fatty acids, etc. are present, recovery of the quaternary ammonium base is more 70 complicated and may require neutralization with mineral acids, vacuum distillation and extraction with hot methyl alcohol.

Since hydrogen sulfide and most hydroxy and carboxyl acids are absorbed substantially completely from hydrocarbon type liquids by treat-

ment with aqueous alkali hydroxide alone, and since these acids make recovery of the quaternary ammonium base relatively complicated, we often prefer to give the liquid to be treated a wash with an aqueous alkali reacting substance, such as 5 tri-potassium phosphate, and/or alkali hydroxide, whereby hydrogen sulfide and oxy acids are removed. The liquid so pretreated is then subjected to the extraction with the quaternary ammonium base, whereby sweetening is effected. 10 The spent quaternary ammonium base containing mercaptans only is then easily regenerated as aforementioned, and substantially pure mercaptans or disulfides can be recovered. Disulfides can be reconverted to mercaptans by known methods, 15 if desired.

We claim as our invention:

1. In the process of separating acid reacting organic substances contained in a hydrocarbon type liquid by extraction with an alkaline reacting 20 substance, the improvement comprising subjecting said liquid to an extraction with a quaternary ammonium base under conditions to form an extract phase containing a substantial amount of the acid substances, and a raffinate phase, and 25 separating said phases.

2. The process of claim 1, in which the quaternary ammonium base is dissolved in water.

3. The process of claim 1, in which the quaternary ammonium base is dissolved in a non-acid 30 solvent which is miscible with water in all proportions, and is substantially non-miscible with the hydrocarbon type liquid.

4. The process of claim 1, in which the base is dissolved in a non-acid solvent which is miscible 35 with water in all proportions and is substantially non-miscible with the hydrocarbon type liquid, said solvent containing a strong inorganic base.

5. The process of claim 1, in which the quaternary ammonium base is dissolved in a non-acid 40 solvent which is miscible with water in all proportions, and is substantially non-miscible with the hydrocarbon type liquid, said solvent containing an alkali hydroxide.

6. The process of claim 1, in which the base is 45 dissolved in an aqueous alkali hydroxide.

7. In the process of sweetening a sour hydrocarbon distillate containing mercaptans in excess of .0004% mercaptan sulfur by extraction with an alkaline reacting substance to remove mercaptans, the improvement comprising extracting said 50 distillate with a sufficient amount of a quaternary ammonium base under conditions to produce an extract phase containing mercaptans, and a raffinate phase containing not more than .0004% 55 mercaptan sulfur, and separating said phases.

8. In the process of separating mercaptans from a hydrocarbon type liquid containing mercaptans and other acid substances, the improvement comprising treating said liquid with an aqueous alkaline reacting substance capable of absorbing said acid substances, whereby the latter are substantially removed from said liquid containing mercaptans, extracting the resulting treated liquid with a quaternary ammonium base under 60 conditions to produce an extract phase containing mercaptans, and a raffinate phase, separating said phases and treating said extract phase to remove mercaptans.

9. In the process of separating mercaptans 70 from a hydrocarbon type liquid containing mercaptans and other acid substances, the improvement comprising treating said liquid with an aqueous alkaline reacting substance capable of absorbing said acid substances, whereby the lat- 75

- ter are substantially removed from said liquid containing mercaptans, extracting the resulting treated liquid with a quaternary ammonium base under conditions to produce an extract phase 5 containing mercaptans and a raffinate phase, separating said phases, subjecting said extract phase to an oxidizing treatment to convert mercaptans to disulfides and separating the disulfides from the base.
- 10 10. In the process of separating acid reacting organic substances contained in a hydrocarbon type liquid by extraction with an alkaline reacting substance, the improvement comprising subjecting said liquid to an extraction with a quater- 15 nary ammonium base having at least one aromatic

radical under conditions to form an extract phase containing a substantial amount of the acid substances and a raffinate phase, and separating said phases.

11. In the process of separating acid reacting 5 organic substances contained in a hydrocarbon type liquid by extraction with an alkaline reacting substance, the improvement comprising subjecting said liquid to an extraction with trimethyl benzyl ammonium hydroxide under conditions to form an extract phase containing a substantial amount of the acid substances and a raffinate phase, and separating said phases.
